HEEL-SEAT FITTING MACHINE

George Hazelton, Leicester, England, assignor to
 United Shoe Machinery Corporation, Borough
 of Flemington, N. J., a corporation of New Jersey

Application October 12, 1938, Serial No. 234,664
 In Great Britain October 25, 1937

14 Claims. (Cl. 12—31.5)

This invention relates to machines for use in the manufacture of shoes and is illustrated as embodied in a machine for trimming the heel ends of attached soles of shoes for reception in channels formed in the breasts of heels of the type described in United States Letters Patent No. 2,121,172, granted June 21, 1938, on an application filed in the name of Fred C. Lovejoy.

It is an object of this invention to provide a machine for quickly and effectively reducing the heel end portions of previously attached soles intended to be interlocked with heels which have sole receiving channels and which will herein-after be referred to as interlocking heels.

15 The interlocking heel has at the upper end of its breast a forwardly projecting lip which is of considerably less width than the upper portion of the breast of the heel, and a sole receiving channel which is formed in the heel breast beneath the lip and terminates in the attaching face of the heel at opposite sides of the lip. In the finished shoe the lip of the heel is positioned between the bottom of the shoe and the attached outsole of the shoe, the rear end of the sole fitting in the channel.

20 In the manufacture of compo shoes having interlocking heels it is customary to form, during the sole-attaching operation, between the bottom of the shoe and the sole of the shoe a pocket which is of suitable size and arranged to receive the lip of the heel to be positioned upon the shoe. In the manufacture of McKay and lock-stitch shoes, however, the pocket is not pre-formed and the lip of the heel is usually forced 25 into the somewhat restricted opening between the shoe bottom and the attached sole in positioning said heel upon the shoe preparatory to attaching the same to said shoe, with the result that the lip is sometimes broken and considerable time is consumed in positioning the heel upon the shoe.

25 With the above conditions in view, and in accordance with a feature of this invention, there is provided in a heel-seat fitting machine a plate for supporting the heel end of an attached sole of a shoe which is to receive an interlocking heel, and a tongue which is associated with and projects forwardly of the plate, and which is constructed and arranged to be interposed between the bottom of the shoe and the central part of the shank portion of the sole of the shoe.

30 The tongue has a shape similar to that of the lip of the heel and when the shoe is positioned in the machine the tongue is located approxi-

mately in the space later to be occupied by the lip of the heel. When the shoe is being positioned in the machine the tongue opens up the restricted pocket between the bottom of the McKay or lockstitch shoe and the rear end of the attached sole of the shoe, thereby facilitating the positioning of the interlocking heel upon the shoe.

35 The tongue has a transversely crowned rearward extension which projects above the forward central portion of a flat sole supporting face of the plate and is of a size and shape to fill up the rear portion of the above-mentioned pre-formed lip-receiving pocket between the bottom of a compo shoe and the rear end of the attached sole of the shoe. The transversely crowned rearward extension of the tongue has a rear face extending widthwise of the sole and disposed at right angles to the flat face of the plate. The tongue and the plate provide a cutting block which effectively supports the sole against the action of a cutter which moves downward past said rear face of the tongue to sever the central part of the sole by a shearing cut 40 progressing toward the lateral portions of the sole and then chops down against the flat face of the plate to continue the trimming cut to the edges of the sole.

45 The various features of the invention will be understood and appreciated from the following detailed description read in connection with the accompanying drawings, in which:

50 Fig. 1 is a perspective view, partly broken away, showing the illustrated machine and a shoe presented thereto;

55 Fig. 2 shows a covered interlocking heel;

60 Figs. 3 and 4 show in perspective the heel seats of compo shoes and the rear ends of the attached soles of which have been reduced for the reception of interlocking heels;

65 Fig. 5 is a perspective view showing the heel seat of a McKay shoe, the heel end of the attached sole of which has been trimmed to the form shown in Fig. 4 for the reception of an interlocking heel;

70 Figs. 6 and 7 are detail views, partly in section and partly broken away, showing the heel ends of the attached soles of shoes being reduced to the forms illustrated in Figs. 3 and 4, respectively;

75 Fig. 8 is a perspective view of the sole-supporting plate illustrated in Figs. 6 and 7;

80 Fig. 9 is a perspective view of the heel-seat portion of a shoe the attached sole of which has been prefitted by the machine disclosed in United

States Letters Patent No. 1,850,149, granted March 22, 1932, on an application filed in my name;

Fig. 10 shows in perspective a portion of a slightly modified machine for trimming material from the rear end of the partially fitted sole of the shoe illustrated in Fig. 9 to prepare the shoe for the reception of an interlocking heel;

Fig. 11 is a perspective view of the shoe illustrated in Fig. 9 after the heel end of its sole has been reduced by the machine of Fig. 10; and

Fig. 12 is a detail view showing the sole-engaging portion of one of the shoe-positioning gages of the machine of Fig. 10.

The illustrated machine will be described with reference to reducing the heel end 14 (Fig. 4) 16 (Fig. 3) of an attached outsole 18, 20, respectively, of a compo shoe 22 and the heel end 19 (Fig. 5) 20 of the attached sole 21 of a McKay shoe 23 for the reception of an interlocking heel 24 (Fig. 2). As described in detail in the above-mentioned United States Letters Patent No. 2,121,172 the interlocking heel 24 has at the upper end of its breast a forwardly projecting lip 26 of less width than the upper end of the breast 28 of the heel, and a channel 30 which underlies the lip and extends from one side of the attaching face 32 of the heel to the other. In the finished shoe to which the heel 24 is attached the lip 26 of the heel is interposed between the outsole 18 (Fig. 4) 20 (Fig. 3) and the bottom of the shoe 22 and the rear end of the reduced sole fits in the channel 30 (Fig. 2) of the heel.

Various methods of reducing the attached sole so that its rear end fits in the channel 30 of the heel 24 positioned upon the shoe have been proposed. In accordance with one method the attached sole 20 of the shoe is trimmed from one side to the other by a straight cut, as illustrated in Fig. 3, forming a rear face 34 spaced a distance 36 from the heel-breast line 38 of the sole, said distance being slightly less than the depth of the channel 30 formed in the breast of the heel. Such practice has been found to be satisfactory when the margins of the sole are previously beveled to a considerable extent, since the beveled lateral margins of the channel-entering portion 40 of the trimmed sole 20 can then be quickly and effectively inserted, without crowding, into the end portions of the channel 30.

When the margins of the sole have not been beveled to a feather edge it is sometimes the practice to form a tab or channel-entering portion 42 (Fig. 4) upon the attached sole 18, the tab having a rear face 44 and beveled lateral margins 46 extending approximately to the ends of the heel-breast line 38 of the sole.

The heel end of the attached sole 20 may be effectively trimmed to the form illustrated in Fig. 3 by a knife 48 (Fig. 6) which has a straight cutting edge 50 and is movable in a vertical path against the upper face 52 of a horizontally arranged sole-supporting plate 54 upon which the heel end of the attached sole of the shoe is positioned. The tab 42 is formed by a knife 56 which is movable in a vertical path against the upper face 52 of the plate 54 and has straight cutting edges 58 and 60 which are offset lengthwise and widthwise from each other and are joined by beveling edges 62.

The sole-supporting plate 54 is positioned and secured in guideways 64 (Fig. 1) of the main frame 66 of the machine through the provision 75 of a pin 68 which fits in a recess (not shown)

of the main frame and has a tapered end (not shown) fitting in a tapered recess (not shown) in the side of the plate. The pin 68 is normally urged to the right, as viewed in Fig. 1, by a spring 70, the forward and rear ends of which are secured to the pin 68 and to a stud 72 secured to the main frame 66. Since three different knives 56 having cutting edges 58 of different lengths are provided to accommodate a run of shoes it will be appreciated that each knife has to accommodate several different sizes of shoes of the run, the soles of the shoes being of different widths. With such an arrangement the beveled margins 46 of the tab 42 formed by the cutting edges 62 of the knife 56 extend to the sides of the sole only in the case of the smallest sole to be operated upon by that particular knife. When the sole of a shoe larger than said smallest sole is operated upon by said knife, narrow shoulders 74 against which the upper breast corners of the heel abut are formed on the sole, the width of the shoulder varying in accordance with the width of the sole. In order to insure that the shoulders 74 of the finished shoe shall not droop away from the shoe upper it is desirable that the next larger knife 58 be used when the width of the shoulders becomes substantial.

In the manufacture of McKay and lockstitch shoes (Fig. 5) in which the sole is attached to the shoe by stitches 76, the operator, after reducing the heel end of the sole to the form shown in Fig. 4 and preparatory to attaching the heel to the shoe, forces the lip 26 of the heel 24 forward into a somewhat restricted pocket 78 formed between the shoe bottom and the rear end of the attached sole of the shoe until the heel is positioned upon the shoe. It has been found that in forcing the lip 26 of the heel 24 into the pocket 78 said lip is sometimes broken. Accordingly it is common practice for the operator to thrust a screw driver, for example, between the shoe bottom and the rear portion of the attached sole between the lines of stitches 76 to open up the pocket so that it will more readily receive the lip and also to insure that there are no undriven tacks extending across the opening, which tacks would prevent the lip from being moved forward to its proper position in the pocket.

Preparatory to reducing the heel end of the attached sole of the shoe, the shoe is located in the machine by centralizing and back gages 80 and 82, respectively, (Fig. 1) identical with corresponding gages of the machine disclosed in United States Letters Patent No. 2,170,842, granted August 29, 1939 on an application filed in the name of William D. Thomas. The back gage 82 is forced rearward by the shoe against a stop (not shown) which is set by an interlocking heel measured in a heel gage (not shown) the arrangement being such that the shoe is so positioned with relation to the path of movement of the knife 48 or 56 that the face 34 or 44 formed on the sole shall engage, or practically engage, the bottom of the channel 30 of the heel positioned upon the shoe. Since the mechanism for locating the back gage 82 in different operative positions in accordance with the interlocking heel measured in the heel gage, is fully disclosed in said Letters Patent No. 2,170,842, it will not be necessary further to describe the same herein.

In operating upon compo work it has been found that when the operator opens up the lip-receiving pocket by forcing the lip of the heel with considerable pressure into said pocket, or by using a screw driver as above described, he fre-

quently splits the adhesive bond securing the lateral margins of the shank portion of the sole to the shoe bottom. Accordingly it is a common practice in the manufacture of compo shoes to 5 insert a fibre piece (not shown) which has a shape similar to that of the lip of the heel to be attached to the shoe, in the space to be occupied by the lip of the heel of the finished shoe, prior to adhesively securing the sole to the shoe. The fibre 10 piece is removed from the shoe after the sole has been attached to the shoe, and leaves a preformed pocket 84 (Figs. 3 and 4) for the reception of the lip 26 of the heel 24 to be attached to the shoe. It will be noted that when the above-mentioned 15 fibre piece is used in preforming the lip-receiving pocket 84 the rear end of the attached sole of the shoe is crowned transversely to a considerable extent and is spaced a slight distance from opposing portions of the shoe bottom.

20 There is also in use a sole-attaching machine which is disclosed in an application for United States Letters Patent Serial No. 282,985, filed July 6, 1939, in the name of Sidney J. Finn, and is provided with a tongue constructed and arranged to fit between the shoe bottom and the rear end portion of the sole being attached by cement to the shoe, the tongue serving to provide the preformed pocket 84.

In order effectively to support the crowned rear 30 end of the trimmed sole of the shoe against the cutting action of the knife 48 or 56, the plate has associated with it, and preferably secured to or integral with its forward end, a forwardly projecting tongue 86. The illustrated tongue 86 is 35 formed integral with the plate 54 and has a flat lower face which is continuous with the lower face of the plate. The tongue 86 is thickest at its rear central part 88 (Fig. 8) which is located a short distance rearward of the front edge 90 40 of the plate and may be referred to as a rearward extension of the tongue. It will be noted that the tongue tapers in thickness from said part 88 toward its sides and its forward end. The rear end 92 of the tongue 86 is disposed at right 45 angles to the flat upper face 52 of the plate 54 and may be described as a shoulder 92 past which the cutting edge 50 of the knife 48 or the cutting edge 58 of the knife 56 moves. The upper edge 94 of the shoulder 92, which may be described 50 as bowed away from the flat face 52 of the plate 54, forms one element of a shearing couple, the knife 48 or 56 forming the other element.

The size of the lip 26 of the interlocking heel 24 varies in accordance with the width of the heel and it is therefore customary to change the plate 54 whenever the corresponding knife 56 is changed, the arrangement being such that the width of the cutting edge 58 of the knife is slightly greater than the width of the shoulder 92 of the tongue 86. In trimming the heel ends of soles of shoes of different sizes and shapes to the form illustrated in Fig. 3 one knife 48 is used, but three interchangeable plates having tongues 86 of different sizes are used.

65 In presenting McKay and lockstitch shoes to the machine the tongue 86 is usually forced with considerable pressure into the pocket formed between the shoe bottom and the rear end of the attached sole, rearward movement of the shoe, which is centralized by the gage 80, being limited when the back gage 82 engages the above-mentioned stop (not shown) of the machine. Accordingly the tongue 86 serves to open up the pocket 70 75 78, which is not preformed as is the pocket 84, for receiving the lip 26 of the heel 24 which is

later to be attached to the shoe. During the heel-seat fitting operation the tongue 86 occupies the same position which the lip 26 occupies in the finished shoe. By opening up the pocket 78 during the heel-seat fitting operation the operator can later quickly and easily force the lip 26 of the heel into the pocket without the danger of breaking the lip.

In operating upon compo work, in which the pocket 84 is usually preformed to the proper 10 shape, as above described, only a slight amount of rearward pressure of the shoe against the tongue 86 is necessary in positioning the shoe upon the plate. It is desirable that the forward portion of the plate shall be thin enough to be 15 interposed between the bottom of a compo shoe and the heel end of a sole attached to the shoe without any tendency to disturb the cement bond ahead of the heel-breast line. By trimming the heel end of the sole progressively from its central 20 portion toward its lateral edges by a shearing action between the curved edge 94 of the tongue 86 and the straight edge of the knife 48 or 56 there is less downward pressure against the plate 54 than there is when the knife trims the sole simultaneously from one side to the other against a flat plate which does not have a tongue. It will be appreciated that the knife 48 or 56 chops down against the flat upper face 52 of the plate 25 30 35 40 45 50 54 in trimming the lateral margins of the sole. The downward pressure against the sole in making such cuts, however, is not very great since the lateral margins of the sole are usually skived to a considerable extent and are therefore quite thin. Moreover, the lateral margins of the plate 54 are effectively supported by adjacent thick portions 95 of the plate and may be made thin and yet stand up under the downward thrust of the knife. Accordingly it is possible to use a thin plate having little if any tendency to break the adhesive bond ahead of the heel-breast line when said plate is provided with the above-described tongue. It will also be noted that were the plate 54 not provided with the sole-supporting tongue 86 the downward flattening-cut pressure of the 45 knife 48 or 56 against the bowed-up rear end of the attached sole of a compo shoe would tend to loosen the cement bond attaching the rear lateral margins of the shank portion of the sole of the shoe to the shoe bottom.

The knife 48 or 56 is secured to a vertically reciprocable slide 96 (Fig. 1) through the provision of a block 98 which is clamped against the shank portion of the knife by a screw 100 threaded into the slide. To insure against vertical displacement of the knife 48 or 56 with relation to the slide 96 during the downward cutting stroke of the knife, a screw 102 which is threaded into the shank portion of the knife is normally in engagement with a flange 104 of the slide. The screw 102 is held in its adjusted position in the shank portion of the knife by a lock nut 106.

When the machine is idle the slide 96 is held in a raised position against a stop 108, secured to the main frame, by a spring 110. Pinned to 65 a rod 112 pivoted upon a bifurcated portion of the slide 96 is a block 114 which is constantly urged rearward by a spring 115 to its vertical operative position below an eccentric 116 secured to a constantly rotating shaft 118. When the machine is idle, as illustrated in Fig. 1, the block 114 is held in its forward inoperative position by a sleeve 120 which is pinned to the rod 112 and has a shoulder 122 in engagement with an opposed shoulder 124 of a latch 126. swinging movement of the block 114 under the action of the spring 115 is limited by the engagement of a pin 128, which is secured to the sleeve 120, with the slide 96.

- 5 The latch 126 is pivoted upon a pin 130 and is normally urged rearward about the pin by a spring 132 the forward end of which is connected to a stud 134 secured to the latch and the rear end of which is connected to a stud 136 secured 10 to a horizontal arm 138 pivoted to the upper end of a bell-crank trip lever 140 mounted upon a bearing pin 142 supported by the main frame. The lower end of the latch 126 is bifurcated to receive the forward end of the arm 138 and has a shoulder 144 which, when the machine is idle, is in engagement with the rear face of the latch 126. The trip lever 140 is normally urged in a clockwise direction as viewed in Fig. 1 by a spring 146, movement of the lever in opposite directions 15 being limited by pins 148 and 150 secured to the main frame. The shaft 118 to which the eccentric 116 is secured is driven by a pulley 152. When the shoe has been positioned in the machine the operator depresses the front end of the trip lever 140 causing the arm 138 to swing the latch 126 forward about the pin 130 and the shoulder 124 of the latch to slide off the shoulder 122 of the sleeve 120. The spring 115 is then rendered effective to swing the block 114 20 rearward so that its upper face 153 is positioned directly beneath the eccentric 116. As the eccentric 116 rotates it depresses the block 114 and the slide 196 causing the knife 48 or 56 to cooperate with the plate 54 and the tongue 86 in 25 trimming the rear end of the attached sole of the shoe for the reception of the interlocking heel 24.

It will be noted that when the sleeve 120 is depressed it swings the forward end of the arm 30 138 downward about its pivotal connection with the trip lever 140 thereby causing the shoulder 144 of the arm 138 to slide off the rear face of the latch 126 and causing the latch to override the upper face of the arm. As the slide 96 is 35 raised after the sole has been trimmed the shoulder 122 of the sleeve 120 engages the shoulder 124 of the latch 126 causing the block 114 to swing forward to its inoperative position shown in Fig. 1 against the action of a spring 115. The machine then comes to rest and cannot be started 40 until the operator raises the bell-crank lever 140 so as to enable the shoulder 144 of the arm 138 again to engage the rear face of the latch 126.

In accordance with another method of procedure I propose to reduce the rear end of the attached sole 154 (Fig. 9) of a shoe 156 by the use of the machine disclosed in the above-mentioned United States Letters Patent No. 1,850,149 to provide a tab 158 such as illustrated in Fig. 9, 45 and then to remove material from the rear end of said tab by a slightly modified machine (Fig. 10) thereby providing a reduced tab 160 (Fig. 11) constructed and arranged to be received in the channel 30 of the interlocking heel 24 to be attached to the shoe. The machine disclosed in said United States Letters Patent No. 1,850,149 is provided with a pair of knives (not shown) which are moved forward to form the beveled faces 162 of the tab 158, and a pair of knives (not 50 shown) which are moved inward from opposite sides of the sole to form heel-breast receiving shoulders 164. Since the machine for forming the tab 158 is disclosed in detail in said United States Letters Patent No. 1,850,149 it will be 55 unnecessary further to describe the same herein.

Since the major portion of the machine for reducing the tab 158 (Fig. 9) to the form illustrated in Fig. 11 is identical with corresponding portions of the machine of Fig. 1, the parts of the machine illustrated in Fig. 10 which are substantially identical with corresponding parts of the machine illustrated in Fig. 1 have been given, respectively, the same numerals, each with an exponent "a".

Instead of positioning the shoe in the machine 10 by the use of the centralizing and back gages 80 and 82 respectively (Fig. 1), the modified machine (Fig. 10) is provided with a pair of work-positioning gages 166 which are movable equal distances toward and away from each other along 15 undercut guideways 168 in the main frame 66. The left and right gages 166, as viewed in Fig. 10, are provided with recesses 167 (one shown) for receiving the lower and upper ends respectively of levers 170 which are secured to the 20 front ends of pins 172 pivotally mounted in bearings (not shown) supported by flanges of the main frame. Downwardly extending levers 176, 178 are secured to the rear ends of the respective pins 172, the levers being pivotally connected to the opposite ends of a link 180 by pins 182 and 184, respectively. The gages 166 are constantly urged toward each other by a spring 186 the right end (not shown) of which is secured to the main frame and the left end of which is 25 secured to a plate 188 pivoted upon the pin 182. In order to open up the gages 166 to position the shoe in the machine a lever 190 is secured to the right pin 172 and is pivoted at its right-hand end to a treadle rod 192.

In order to position the pretrimmed sole 154 of the shoe 156 illustrated in Fig. 9 in the machine preparatory to reducing the tab 158 to form the tab 160 (Fig. 11) the operator depresses the treadle rod 192 to move the gages 166 equal distances away from each other and then places the shoe in approximately its proper position in the machine with the tab 158 overlying the sole-supporting surface 52^a of the plate 54^a and with the tongue 86^a interposed between the shank portion 45 of the sole and the bottom of the shoe. The treadle 192 is then released causing the end faces 194 of the gages 166 to be forced against the respective beveled faces 162 of the tab 158, thereby centralizing the tab of the attached sole of 50 the shoe upon the plate 52^a. The operator then moves the shoe rearwardly until the front faces 196 of the gages engage the respective heel-breast receiving shoulders 164 of the sole. With the sole thus positioned the operator depresses the 55 trip lever 140 of the machine causing the knife 48^a to reduce the tab 158 to the form shown in Fig. 11. The distance between the front faces 196 of the gages 166 and the path of vertical movement of the knife is such that the end face 198 of the reduced tab 160 substantially engages the bottom of the channel 30 of the interlocking heel 24 when the same has been positioned upon the shoe with its upper breast corners in engagement with the heel-breast receiving shoulders 60 65 164.

Having described the invention, what I claim as new and desire to secure by Letters Patent of the United States is:

1. In a heel-seat fitting machine, a plate to 70 be interposed between the bottom of a shoe which is to receive an interlocking heel and the heel end of an attached sole of the shoe, and an associated tongue which projects forwardly of the plate and is of less width than the sole of 75

the shoe, said tongue being arranged to be interposed between the shoe bottom and the rear median part of the shank portion of the attached sole supported by and positioned upon the plate and between adhesive bonds or lines of stitches securing the respective rear lateral margins of the shank portion of the sole to the shoe bottom.

2. A heel-seat fitting machine comprising a plate for supporting the heel end of an attached sole of a shoe to which an interlocking heel is to be attached, a forwardly projecting tongue associated with the plate and constructed and arranged to be interposed between the bottom of the shoe and the shank portion of the attached sole, said tongue having a face which is positioned adjacent to the plate, and a knife movable in a predetermined path past said face of the tongue and against the plate to reduce the heel end of the sole for reception in a channel formed in the breast of the heel.

3. A heel-seat fitting machine comprising a plate having a flat upper face over which may be positioned the heel end of an attached sole of a shoe to which an interlocking heel is to be attached, an associated tongue projecting forwardly of the plate and constructed and arranged to be interposed between the bottom of the shoe and the shank portion of the attached sole, said tongue having a lower face which is substantially continuous with the lower face of the plate and a rear face which is positioned above and adjacent to the upper face of the plate, and a knife movable in a predetermined path past the rear face of the tongue and against the upper face of the plate to reduce the heel end of the sole for reception in a channel formed in the breast of the heel.

4. A heel-seat fitting machine comprising a plate having a flat upper face and a thin forward portion, means for positioning the heel end of an attached sole of a shoe to which an interlocking heel is to be attached over said face of the plate, a tongue which is associated with the plate and which projects forwardly and rearwardly of said front portion of the plate and has at its rear end an edge extending above the upper face of the plate, the forwardly projecting portion of the tongue being constructed and arranged to be interposed between the bottom of the shoe and the shank portion of the sole of the shoe, and a knife movable in a predetermined path past said edge of the tongue and against the upper face of the plate to trim the rear end of the sole for reception in a channel formed in the breast of the heel.

5. In a heel-seat fitting machine, means for supporting the heel end of an attached sole of a shoe to which an interlocking heel is to be attached, said means comprising a tongue which is of considerably less width than the sole of the shoe and is arranged to open up and to be received within a pocket formed between the bottom of the shoe and the rear median part of the shank portion of the attached sole and between adhesive bonds or lines of stitches securing the rear lateral margins of the shank portion of the sole to the shoe bottom, and a knife for reducing the heel end of the sole for reception in a channel formed in the breast of the heel.

6. A heel-seat fitting machine comprising means for supporting the heel end of an attached sole of a shoe to which an interlocking heel is to be attached, said means comprising a tongue

which is constructed and arranged to be positioned in a pocket formed between the bottom of the shoe on the one hand and the shank and heel-end portions of the attached sole on the other hand, said tongue having a rear face which intersects the sole-engaging face of the tongue and forms a sharp edge therewith, and a knife movable in a predetermined path past said edge of the tongue to trim the median portion of the sole widthwise by a shearing cut and then into engagement with other portions of said means to trim the lateral margins of the sole by die cuts.

7. A heel-seat fitting machine comprising means for supporting the heel end of an attached sole of a shoe to which an interlocking heel is to be attached, a knife movable in a predetermined path, mechanism for positioning the heel end of the sole upon said means with relation to the path of movement of the knife, said means comprising a forwardly projecting tongue which is constructed and arranged to lie between the bottom of the shoe on the one hand and the shank and heel-end portions of the sole on the other hand, said tongue having a rear face, and means for moving the knife past said rear face of the tongue and then against other portions of said means to trim the rear end of the sole for reception in a channel formed in the breast of the heel.

8. In a heel-seat fitting machine, a knife movable in a predetermined path, means for supporting an attached sole of a shoe which is to receive an interlocking heel against the action of said knife, said means comprising a thin plate constructed and arranged to be positioned between the bottom of the shoe and portions of the sole extending rearward of its heel-breast line, and a relatively thick tongue formed integral with the plate and constructed and arranged to be positioned in a pocket formed between the shoe bottom and median portions of the sole which are located immediately rearward and forward of the heel-breast line of the sole.

9. A heel-seat fitting machine comprising a knife for trimming the rear end of an attached sole of a shoe for the reception of an interlocking heel, and means for supporting the sole against the action of said knife, said means comprising a thin plate having a flat upper face and an associated tongue which is considerably narrower than said plate and which extends above said face and also extends forward and rearward of the front end of the plate.

10. A heel-seat fitting machine for trimming an attached sole of a shoe for the reception of an interlocking heel having, in combination, a plate constructed and arranged to be received between the bottom of the shoe and the tab formed at the rear end of the sole of the shoe, a tongue which is associated with the plate and is constructed and arranged to be interposed between the shoe bottom and the shank portion of the attached sole, a pair of gages for positioning the tab widthwise and lengthwise upon the plate, and a knife for reducing the positioned tab upon the plate for reception in a channel formed in the breast of the heel, said gages being movable toward and away from each other and being constructed and arranged to engage a corresponding heel-breast receiving shoulder on the sole and a lateral margin of the tab.

11. A heel-seat fitting machine comprising a thin plate having a flat face, a relatively thick tongue which is formed integral with the plate

- and which projects forwardly of the plate and has its rear portion extending above and positioned between the forward lateral portions of said face, and a knife movable in a predetermined path past the rear end of the tongue and against said flat face of the plate to sever the rear end of the attached sole of a shoe supported by the plate and the tongue for reception in a channel formed in the breast of an interlocking heel to be attached to the shoe.
12. A heel-seat fitting machine comprising a plate having a flat upper face, means for positioning the heel end of an attached sole of a shoe to which an interlocking heel is to be attached with relation to said plate, an associated tongue projecting forwardly of the plate and constructed and arranged to be interposed between the bottom of the shoe and the shank portion of the attached sole, said tongue having a flat lower face which is substantially continuous with the lower face of the plate and having an upper face which is beveled widthwise and lengthwise from its rear central portion, said tongue also having a rear face which is disposed at approximately right angles to the flat upper face of the plate and extends widthwise of the sole of the positioned shoe, and a knife movable in a predetermined path past the rear face of the tongue and against the upper face of the plate to reduce the heel end of the sole for reception in a channel formed in the breast of the heel.
13. In a heel-seat fitting machine, a cutting bed constructed and arranged to be received between the bottom of a shoe which is to receive

an interlocking heel and the heel end of the attached sole of the shoe, means for positioning the shoe relatively to said cutting bed, a knife having a cutting edge lying approximately in a plane, said cutting bed comprising a thin plate 5 having a flat upper face, a tongue which is associated with the plate and projects forwardly of said plate, said tongue being constructed and arranged to lie between the shoe bottom and the shank portion of the sole when the shoe is positioned with relation to the cutting bed, a transversely crowned extension of the tongue projecting above said face of the plate and positioned between the front lateral portions of said face, said extension having a rear face terminating in an edge, and means for moving the cutting edge of the knife past the edge of said extension and then against said flat face of the plate to reduce the rear end of the sole for reception in a channel formed in the breast of said heel. 10

14. In a heel-seat fitting machine, a cutting bed comprising a thin plate having a flat face and a relatively thick transversely crowned portion which extends above said face and is arranged between the forward lateral portions of the plate, 25 said crowned portion having a rear face extending transversely of the plate and disposed at approximately right angles to said face of the plate, a knife movable in a predetermined path past the rear face of said crowned portion and against the flat face of the plate, and a tongue formed integral with and projecting forwardly of the plate. 30

GEORGE HAZELTON.
